DESIGN FOR A CIGAR PACKAGE

Anthony Suraci, Scranton, Pa.

Application November 24, 1945, Serial No. 124,050

Term of patent 14 years

(Cl. D80—5)

To all whom it may concern:

Be it known that I, Anthony Suraci, a citizen of the United States, residing in Scranton, county of Lackawanna and State of Pennsylvania, have invented a new, original, and ornamental Design for a Cigar Package, of which the following is a specification, reference being had to the accompanying drawing, forming part thereof.

In the drawing:

Fig. 3 is a reduced scale rear elevational view; and

Fig. 4 is a top plan view.

I claim:

The ornamental design for a cigar package, as shown.

ANTHONY SURACI.
